UNITED STATES PATENT OFFICE.

HELENA J. JONES AND FRANK T. JONES, OF BALTIMORE, MARYLAND.

ELECTRIC SIGNAL FOR RAILROADS.

No. 820,577.

Specification of Letters Patent.

Patented May 4, 1909.

Application filed October 1, 1908. Serial No. 455,596.

To all whom it may concern:

Be it known that we, HELENA J. JONES and FRANK T. JONES, citizens of the United States, residing at Baltimore, in the State of Maryland, have invented certain new and useful Improvements in Electric Signals for Railroads, of which the following is a specification.

This invention relates to improvements in electric signals for railroads.

One object of the invention is to provide an improved arrangement of block signals which will normally, and during the absence of a train from the block, be maintained in the safety condition by a closed or complete circuit, which circuit upon the entrance of a train into the block will be shunted from the signal and set the latter to danger.

Another object is to provide an improved construction of electro-mechanical signal mechanism which will electrically maintain the signal in a safety position and mechanically operate said signal to set it in a danger position so that in case the circuit is tampered with or in any way disarranged or broken the signal will automatically be set to the danger position.

Another object is to provide an improved construction of signal mechanism and to combine therewith an improved construction of air brake operating mechanism whereby during the absence of a train from a block the air-brake device on a train about to enter said block will be electrically maintained in an inoperative position and will be mechanically operated when it attempts to enter a block while a train is in said block.

It will be obvious that the inventive idea here disclosed may be readily utilized to guard trains when approaching bridges or switches in that the circuit would be broken by the opening of the switch or bridge and thus set the signal to the danger position.

The invention is illustrated in the accompanying drawings in which,—

Figure 1, illustrates diagrammatically the application of the invention to a section or block of a railroad and shows the signal mechanism in the safety position. Fig. 2, is a similar view with the exception however that the signal mechanism is shown in the danger position. Fig. 3, is a diagrammatic view of the circuits and devices carried by the engine or motor for effecting an operation of the air brakes. Fig. 4, is a plan view of the track mechanism for operating

the air-brakes, and Fig. 5 is an enlarged detail in side elevation of the trip mechanism in the motor or engine for venting the train-line to effect an operation of the air brakes. 60

In illustrating the invention we have shown the same as applied to a double-track road where the trains travel in one direction only on the rails but it is obvious that the invention may be applied to a single track 65 road by merely duplication of the mechanism and providing like mechanism and electric connection at each end of the block.

In carrying out the invention for a double track road we provide at the entrance to 70 each block short insulated rail sections, 1, and, 2, which are preferably arranged directly opposite each other. From the said sections to the opposite end of the block the rails, 3, may be of the ordinary form. 75

Preferably adjacent the entrance to each block we provide a battery, 4, or other source of electrical energy, which in the present instance is shown housed in a box-like structure, 5. From one side of this battery we run a wire, 6, which terminates at 80 and is connected with the insulated rail section, 1, while a wire, 7, extends from the opposite side of the battery and electrically connects the other rail section, 2. 85

A semaphore signal-arm, 8, is pivotally mounted on a suitable post, 9, and is operated by means of a rod, 10, the lower end of which is pivotally connected to the free end of pivoted armature, 11. An electro-magnet, 90 12, has position adjacent the said armature, 11, so that when energized the magnet will attract the armature and throw the signal arm, 8, to the safety position as shown in Fig. 1. In the present instance when in 95 the safety position the semaphore arm, 8, is in an upwardly-inclined position but it is obvious that by the interposition of cranks and levers it may have a downwardly-inclined position. 100

The electro-magnet, 12, is electrically connected by wire, 13, to the insulated rail-section, 2, so that from the battery, 4, the current may flow through wire, 7, rail-section, 2, and wire, 13, to one side of the electro-magnet, 12. At the other side of the said magnet, 12, we connect a wire, 14, which runs or extends to one side of another electro-magnet, 15, which forms part of an air-brake operating mechanism. The track portion of this latter mechanism comprises a contact plate, 16, having position at one side 105 110

of the road bed as clearly shown in Figs. 3 and 4 and to which an L-shaped bar, 17, is connected so as to project in a plane beneath the magnet, 15. A similarly-shaped bar, 18, is attached to the rail, 3, so that the two ends of the bars, 17, and 18, will terminate adjacent but spaced slightly from each other. An armature, 19, is pivotally mounted in any suitable manner so as to be operated by the magnet, 15, and also so that when the magnet becomes deenergized it will drop and close the gap between the adjacent ends of the bars, 17, and, 18, as shown in Fig. 2.

15 The energization of the magnet, 15, and the elevation of the armature, 19, is effected by current that passes through wire, 14, to the magnet and then from the magnet by wire, 20, to a main magnet, 21, in the box, 5.

20 This main electro-magnet, 21, operates an armature, 22, the free end of which when the armature is drawn up against the magnet will contact with a spring plate, 23, so that when in this operated condition the current will flow from wire, 20, through magnet, 21, by wire, 24, to armature, 22, through the latter to contact plate, 23, and then by a wire, 25, to the rail section, 1, and from the latter through wire, 6, back to battery, 4, and thereby complete the circuit. It is thus to be understood that the circuit includes all three electro-magnets, 12, 15, and, 21, and that the safety signal is maintained so long as all the magnets are energized and if, for any cause, the circuit should become broken the deenergization of the magnets results and the danger signal thereby set.

When a train enters a block a short circuit is established by means of the wheels, 26, and axle, 27, so that the circuit embraces battery, 4, wire, 6, rail-section, 1, wheels and axle, 26, and, 27, rail-section, 2, and wire, 7, back to battery. This short-circuit effects a deenergization of all the magnets and results in setting the signal arm, 8, in the horizontal or danger position. This danger signal remains set until the train reaches the end of the block where it will reestablish the circuit and again energize the magnets as will now be explained.

At the end of the block we insulate one rail, 3, from a short rail-section, 28, and we provide a wire, 29, which connects rail, 3, with wire, 24, or one side of the main magnet, 21. We also provide a wire, 30, from rail-section, 28, back to battery wire, 6, so that as the wheels of the train pass from rail, 3, onto rail, 28, the circuit will be through wire, 29, to magnet, 21; wire, 20, to magnet, 15; wire, 14, to magnet, 12; wire, 13, to rail-section, 2, and wire, 7, to one side of battery, 4; then from the other side of the battery by wires, 6, and, 30, back to rail-section, 28. This completion of the cir-

cuit through all the magnets by the train leaving a block will cause the magnets to again be energized and the arm, 8, again set in the safety position.

In case the engineer of a train should fail to see or correctly distinguish the danger signal while another train is in the block he is about to enter, we have provided the air-brake operating device heretofore referred to and the track-portion of which has been described. We will therefore now proceed to briefly describe the train portion of this air-brake apparatus.

On the engine or motor and interposed or connected to the train line or pipe, 31, we place a valve, 32, of suitable construction to effect a venting of the train pipe air. This valve is preferably located in the cab and in the present instance is provided with two arms 33 and 34,—the latter being provided with a weight. An electro-magnet, 35, is sustained in any suitable manner adjacent the valve, 32, and operates, when energized to attract and hold an armature, 36. This armature is provided with a hook-shaped end which projects beneath and forms a support for the free end of the valve arm, 33, so as to hold said arm in such a position as not to affect the train-pipe pressure. A spring, 37, serves to exert a pull on the hook-end of the armature but is not of sufficient strength to pull the armature away as long as the magnet is energized.

A battery, 38, is provided on the engine or motor and wires, 39, and, 40, respectively connect the opposite sides of the battery with the poles of the magnet, 35, so as to keep the same energized and hold the armature beneath the lever, 33. From one side of the battery, 38, we run a wire, 41, to the axle or wheel, 42, while another wire, 43, runs from the other side of the said battery and connects with a yieldingly-operated roller, 44, which we mount at the side of the pilot truck so that it may contact with the plate, 16, at the side of the rail, 3.

It should be remembered that when a train enters a block, the magnet, 15, becomes deenergized and the armature, 19, closes the gap between bars, 17, and, 18. It will also be remembered that the bar, 17, is carried by the plate, 16, while the bar, 18, is carried by the rail, 3. When therefore the engine passes plate, 16, on its way into a block when there is another train in said block the current from the battery, 38, on the engine will pass through wire, 41, wheel, 42, rail, 3, bar, 18, to bar, 17, then through plate, 16, roller, 44, wire, 43, and back to battery. This shifting of the current through the circuit of least resistance will cause the deenergization of the magnet, 35, and will permit the spring, 37, to retract the armature, 36, and thereby relieve the arm, 33, of the valve and the latter to open to vent the train-pipe and

apply the brakes. It will be understood that the reason this air-brake mechanism is not operated when the block is clear is that when clear, the magnet, 15, is energized and the armature, 19, is held up and although the roller, 44, on the engine will contact with plate, 16, the circuit will not be completed through the rail because of the gap between bars, 17, and, 18.

10 Having thus described our invention what we claim and desire to secure by Letters Patent is,—

1. In a device of the character described the combination with the two rails, of a source of electrical energy; connections between the source of energy and the two rails; a contact plate at the side of the rail and adjacent the entrance to the block; contact bars carried by the plate and rail and normally spaced from each other; an armature for closing the gap between said bars; a magnet for normally holding the armature away from the said bars; a normal circuit including the source of energy, the rail sections, and said magnet whereby to normally hold the armature out of contact with the said bars; a valve on the motor vehicle for controlling the air to the brakes; an electro-magnet also on the vehicle for controlling said valve to normally hold it in the inoperative position; a battery also on the vehicle for normally energizing said magnet; a contact device also on the vehicle to contact with the plate at the side of the rails; a connection between the contact device and the battery on the vehicle and another connection from the said vehicle battery to the wheel of the vehicle.

2. A railway block signal comprising the two rails; a battery; connections between the battery and the two rails; an electro-magnetic signal device; a valve on the motor vehicle for actuating the air-brakes; an elec-

tro-magnet for controlling said valve to hold it in the inoperative position; a battery on the vehicle for normally energizing said magnet; a contact device also on the vehicle and having a connection with the battery on the vehicle; another connection from the vehicle battery to the wheel of the vehicle; a contact plate at the side of the rail and adjacent the entrance to a block; contact bars carried by the plate and rail and being normally spaced from each other; an armature for closing the gap between said bars; a magnet for normally holding the armature away from the bars, and a circuit including the battery, rail-sections, signal device and last-named magnet whereby the interruption of the circuit will permit the armature to complete the circuit through the bars with the battery on the vehicle and thereby de-energize the magnet on the vehicle and permit the operation of the valve thereon.

3. A railway block signal comprising a battery; two insulated rail-sections at the entrance to a block; a signal device operated by an electro-magnet; a contact plate adjacent the rail; an armature for closing a circuit through the rail and contact plate; an electro-magnet for operating the armature; a third electro-magnet and armature operated by the latter magnet, a circuit embracing the battery, both rail sections and all three magnets whereby to electrically maintain the signal in the safety condition and to electrically maintain the armature between the contact plate and rail in the open position.

In testimony whereof we affix our signatures in presence of two witnesses.
